BURNER TIP CLEANER
Filed April 22, 1928

L. E. Hood, Inventor

By Clarence A. O'Brien.

Attorney

UNITED STATES PATENT OFFICE.

LAWRENCE EDWARD HOOD, OF NUTTER FORT, WEST VIRGINIA.

BURNER-TIP CLEANER.

Application filed April 22, 1926. Serial No. 103,870.

The present invention relates to improvements in cleaning devices particularly for use in cleaning burner tips of miners' carbide lamps.

5 One of the important objects of the present invention is to provide a simple device which may be readily and easily attached to the reflector of a carbide lamp which normally is held in an inoperative position so 10 as not to interfere with the ordinary use of the lamp, the cleaning device being adapted to be readily and easily placed in position for facilitating the cleaning of the bore of the burner tip which usually becomes 15 clogged with carbon deposits.

Another important object of the invention is to provide a cleaning device of the above mentioned character which will save considerable time and labor in cleaning the 20 burner tip of a carbide lamp, the device being at all times readily accessible.

A still further object is to provide a cleaner of the above mentioned character which is simple in construction, inexpensive, strong 25 and durable, and further well adapted to the purpose for which it is designed.

Other objects and advantages of the invention will become apparent during the course of the following description taken in 30 connection with the accompanying drawing.

In the accompanying drawing forming a part of this application and in which like numerals designate like parts throughout the several views:

35 Figure 1 is a front elevation of a portion of a miner's carbide lamp showing the present invention attached thereto and in an inoperative position, and

Figure 2 is a view partly in elevation and 40 partly in section of the device showing the same in its operative position.

In the drawing wherein for the purpose of illustration is shown the preferred embodiment of my invention, the numeral 1 designates the usual reflector of a miner's carbide lamp and the burner tip which projects from the center thereof is indicated 45 at 2. The usual bore or passage formed in the burner tip and through which the gas passes is illustrated at 3.

The bore or passage 3 of the burner tip 2 frequently becomes clogged up by the formation of carbon and as a result of such obstructions, the burner tip becomes inoperative. At the present time the miner usually carries on his person a piece of wire 50

which is preferably pointed at one end and this piece of wire is ordinarily used in cleaning out the bore of the burner tip so that the carbon deposits will be scraped or otherwise removed in order to provide an unobstructed passage for the gas. This necessitates the loss of considerable time and labor, and the present invention has for its principal object to provide a simple and efficient device which may be readily and easily attached to a carbide lamp and will at all times be accessible for positioning the cleaner element over the bore of the burner tip whenever it becomes necessary to clean the 70 burner.

My improved device comprises a bracket 4 in the form of a flat strip of spring metal, the inner end thereof being pivotally secured to the reflector 1 at a point adjacent 75 the burner tip 2 as illustrated at 5. A spring clip 6 is formed at the outer end of the strip comprising the bracket 4 and this spring clip is adapted for cooperation with the peripheral edge of the reflector, for normally holding the device in an inoperative position and in a rigid manner as is clearly shown in Figure 1. A finger piece 7 is formed on the extreme outer end of the strip comprising the bracket in order to 80 facilitate the disengagement of the spring clip 6 from the peripheral edge of the reflector 1 as will be more fully described.

Carried by the intermediate portion of the pivoted bracket 4 is the cleaner member 80 designated generally by the numeral 8, the same comprising a body portion 9 provided with a lateral extension 10 which affords a means for securing the cleaner member to the intermediate portion of the bracket 4. 90 The extension 10 may be secured to the bracket 4 in any suitable manner as by way of solder or the like. The lower end of the body portion 9 tapers gradually downwardly and the upper portion of the body 100 is externally threaded as clearly shown in Figure 2. A longitudinally extending bore 11 is formed in the body 9 and the upper portion of the bore is enlarged as shown at 12.

The cleaning element per se comprises a needle 13 which extends downwardly through the bore of the body, the lower end of the needle being pointed and adapted to enter the bore 3 of the burner tip 2 as 110 will also be presently described.

A handle 14 is formed on the upper end

of the needle 13 and a shoulder 15 is also formed on said needle at a point adjacent the lower end of the handle. An expansible coil spring 16 encircles the intermediate portion 5 of the needle 13 and is disposed between the shoulder 15 and the lower portion of the enlarged portion 12 of the bore formed in the body 9.

An internally threaded cap 17 is threaded 10 on the upper end of the body 9 and the handle portion 14 is adapted for slidable movement through the top of the cap. The upper face of the shoulder 15 also engages the under face of the top of the cap 17 in the manner as clearly shown in Figure 2. The coil spring 16 normally holds the needle in its uppermost position in the body 9 of the cleaner 8 so that the pointed lower 15 end of the needle does not protrude below the lower end of the body portion 9.

As heretofore stated, the device is normally disposed in the position shown in Figure 1 of the drawing, and the spring clip 6 being in engagement with the peripheral edge of the reflector 1 of the carbide lamp, there will be no possibility of the device being accidentally moved from its inoperative position, thus preventing any 20 possibility of the cleaning device interfering with the burner tip of the carbide lamp when the same is properly functioning.

However, should the bore of the burner tip become clogged with carbon so that the gas cannot pass therethrough and become 25 ignited at the tip of the burner, the spring clip 6 is disengaged from the peripheral edge of the reflector 1 by grasping the handle portion 7 and by swinging the bracket 4 upwardly on its pivot 5 so that the lower 30 tapered end of the body 9 will be disposed directly over the outer end of the burner tip 2 in the manner as clearly shown in Figure 2.

By then depressing on the handle portion 45 14, the pointed end of the needle 13 will enter the bore 3 of the burner tip and thus remove the accumulations of carbon therein so that the gas passage will again be opened. When pressure is released from the handle 50 14, the coil spring 16 will return the needle to its normal position within the body portion 9, and the bracket 4 may then be swung outwardly to its normally inoperative position, and the spring clip 6 brought into 55 engagement with the peripheral edge of the reflector 1 so that the burner tip cleaning device will be maintained in a rigid inoperative position to permit the ordinary use of the carbide lamp in the usual manner.

60 It will thus be seen from the foregoing description, that I have provided a novel yet simple attachment for a carbide lamp to facilitate the cleaning of the bore of the burner tip without the loss of any considerable length of time or labor, the device be-

ing so arranged on the carbide lamp as to at all times be readily accessible.

While I have shown the preferred embodiment of my invention it is to be understood that minor changes in the size, shape 70 and arrangement of parts may be resorted to without departing from the spirit and scope of the appended claims.

Having thus described the invention, what I claim as new and desire to secure by Letters Patent is:—

1. The combination with a carbide lamp including a burner tip, and the usual reflector, of a bracket pivotally secured at its inner end to said reflector adjacent the burner tip, a cleaning member carried by the bracket and adapted to be disposed in an operative position over the burner tip when said bracket is in one position, and means associated with the outer free end of the bracket for normally holding the same in an inoperative position.

2. The combination with a carbide lamp including a burner tip, and the usual reflector, of a bracket pivotally secured at its inner end to said reflector adjacent the burner tip, a cleaning member carried by the bracket and adapted to be disposed in an operative position over the burner tip when said bracket is in one position, means associated with the outer free end of the bracket for normally holding the same in an inoperative position, said means comprising spring clip associated with the outer free end of the bracket and adapted for engagement with the peripheral edge of said reflector.

3. In combination with a carbide lamp including a burner tip, and the usual reflector, of a bracket formed from a single strip of 105 spring metal, said bracket being pivotally secured at its inner end to said reflector at a point adjacent the burner tip, a cleaning element carried by the intermediate portion of said bracket and adapted to be disposed in an operative position over the burner tip when the bracket is swung upwardly, a spring clip formed in the outer end portion of said strip and adapted for engagement 110 with the peripheral edge of the reflector for normally holding the bracket and the cleaning element in an inoperative position and against swinging movement, and a handle formed on the outer end of the strip to facilitate the disengagement of the spring 115 clip from the peripheral edge of said reflector.

4. The combination with a carbide lamp including a burner tip, and the usual reflector, of a bracket pivotally secured at 125 its inner end to said reflector at a point adjacent the burner tip, means associated with the outer end of said bracket and cooperating with the peripheral edge of the reflector for normally holding the bracket 130

in inoperative position against swinging movement, and a cleaning member carried by the intermediate portion of said bracket, said cleaning member including a body portion provided with a central bore, the upper portion thereof being enlarged, a needle extending through the bore of the body, a cap threaded on the upper end of said body, a handle formed on the upper end of said needle and adapted for slidable movement

through said cap, an annular shoulder formed on the needle at a point below said handle, said shoulder being adapted for engagement with the bottom face of the cap, and a coil spring encircling said needle and disposed in the upper enlarged portion of the bore for normally holding the needle in a retracted position in the body portion. ¹⁵

In testimony whereof I affix my signature.

LAWRENCE EDWARD HOOD.
